FABRIC TAKE-OFF DEVICE FOR FULL FASHIONED KNITTING MACHINES

Filed June 21, 1930

FIG. 1.

FIG. 2.

UNITED STATES PATENT OFFICE

GUSTAV GASTRICH, OF WYOMISSING, PENNSYLVANIA, ASSIGNOR TO TEXTILE MACHINE WORKS, OF WYOMISSING, PENNSYLVANIA, A CORPORATION OF PENNSYLVANIA

FABRIC TAKE-OFF DEVICE FOR FULL FASHIONED KNITTING MACHINES

Application filed June 21, 1930. Serial No. 462,801.

My invention relates to full fashioned knitting machines, and more particularly to the fabric take-off mechanism therefor.

As well known, full fashioned knitting machines comprise a series of similar sections which simultaneously knit separate stocking fabrics or webs that are drawn off the needles by take-off mechanism ordinarily consisting of a common fixedly mounted weight operated shaft provided with individual fabric attaching devices.

During the formation of the loops, the needle bars of the various sections move vertically as well as horizontally relatively to this take-off shaft, with consequent tensioning of the webs which causes lengthening of the loops and bending of the needles. Various spring arrangements have heretofore been utilized to overcome these detrimental effects but all such devices are more or less troublesome, and do not satisfactorily overcome the undesirable effects mentioned.

The primary object of my invention is to provide novel fabric take-off means adapted to prevent variation in the tensioning of the fabric during cyclic operation of the needles, and I accomplish this by movably mounting such means and actuating it substantially in accordance with the movements of the needle bar.

The invention comprises the novel elements, features of construction and arrangement of parts in cooperative relationship as fully disclosed by the following detailed description and accompanying drawings of one embodiment thereof, reference to which will make the above and other objects, as well as attendant advantages more readily apparent.

Referring to the drawings:—

Fig. 1 is a partial cross-sectional view through one section of a full fashioned knitting machine having my invention applied thereto.

Fig. 2 is a fragmentary plan view of certain elements forming part of my invention.

In the drawings 5 indicates the needles, 6 the needle bar which is fixed to a needle bar fork 7 pivotally connected at 8 to a link 9 in turn detachably connected at 10 to a needle bar rocker arm 11 pivoted on a fixed shaft 12,

and provided with a roller 13 at its lower end that cooperates with a cam 14 on machine cam shaft 15. The elements just described provide for periodic reciprocation of the needle bar in a horizontal direction forward and rearward.

Pivottally secured to a needle bar bracket 16 is a lever 17 which is fulcrumed on a fixedly mounted shaft 18 and also provided with a cam roller 19 that cooperates with a cam 20 to periodically move the needle bar in a vertical direction. Anchored springs 21 and 22 connected to the lower extremities of rocker arm 11 and the lever 17 respectively, function to maintain the cam rollers 13 and 19 in contact with the cams 14 and 20 at all times.

The mechanism so far set forth is old and well known and forms no part of my invention except in so far as it is used in combination and cooperates with the fabric take-off device later described.

Ordinarily, in the so called "leggers" the fabric take-off device comprises a rotary shaft 23 which is operated in well known manner by a weight, connected thereto by a rope (not shown) and on which as many fabric take-up rolls 24 are secured as there are needle bars. Fabric attaching means being generally connected with each take-up roll 24 in the form of straps 25 provided with hooks 26 at their outer ends adapted to hold a rod 27 that passes through the welt 28 of the stocking fabric or web 29.

In order to prevent periodic stretching strain upon the fabric during movement of the needles 5 through their cycle of operation, various spring arrangements have heretofore been incorporated either directly in the rolls 24, to permit the same to slightly turn under unusual tension, or in the straps 25 to permit them to give under similar conditions, and these somewhat relieved the strain on the stocking fabric, however, it will be apparent that such spring arrangements are bound to cause an excessive amount of strain or tension in the delicate silk fabric, which is obviously undesirable.

In order to avoid such straining of the fabric, I have provided a take-off device which

is movably mounted and actuated substantially in accordance with the movements of the needles 5. To this end, I provide the usual take-off shaft 23 and operate it as heretofore in well known manner, however, instead of rigidly mounting the same I provide movable bearings 30 therefor which may be directly mounted on the shaft 12, or integrally formed with rocker arms 11, so as 16 to move in unison with the latter.

It will be noted, that the lever arrangement which moves the needle bar 6, forms a substantial mechanical parallelogram and that therefore, the horizontal reciprocatory 15 movements imparted to the needles and bearings 30, and consequently the fabric take-off means generally, are practically synchronized; all parts moving in unison and in the same direction at all times.

20 In order that possible slight variations in tension, due to operating or other differences in the various sections of the machine can be compensated for, the rolls 24 are adjustably mounted on the shaft 23 by means of set 25 screws 31 passing through collars or flanges 32 forming part of the rolls 24.

Of course the fabric take-off device shown and described may be changed, modified, and connected in various ways to attain the same 30 desirable advantages, without departing from the invention herein set forth and hereinafter claimed.

I claim:

1. In a straight knitting machine, the combination with a reciprocatively operated needle bar, of a fabric take-off roll correspondingly reciprocated to maintain a relatively fixed distance between said roll and bar.

2. In a straight knitting machine, the combination with a movable needle bar, of a movable fabric take-off device, and means for similarly actuating said needle bar and device in unison.

3. In a straight knitting machine, the combination with a movable needle bar, of a movable fabric take-off device, and common means for similarly actuating said needle bar and device.

4. In a straight knitting machine, the combination with a movable needle bar, of a movably mounted fabric take-off device and means connecting said needle bar and device for similar reciprocative movements.

5. In a straight knitting machine, the combination with a movable needle bar, of a fabric take-off device comprising a rotary shaft provided with fabric attaching means, a movable mounting for the shaft, and means for similarly reciprocating said needle bar and shaft simultaneously.

6. In a straight knitting machine, the combination with a movable needle bar, of a fabric take-off device comprising a rotary shaft having a fabric take-off roll adjustably 65 mounted thereon, fabric attaching means con-

nected with said roll, and cam means for simultaneously actuating said needle bar and take-off device.

7. In a straight knitting machine, the combination with a plurality of movable needle bars, of fabric take-off means comprising a rotary shaft provided with separate adjustably mounted take-off rolls one for each needle bar, fabric attaching means connected with each roll, a movable mounting for said shaft, and common means for actuating said needle bars and mounting.

In testimony whereof I affix my signature.

GUSTAV GASTRICH.
